UNITED STATES PATENT OFFICE.

MICHAEL DEBATIN, OF ST. LOUIS, MISSOURI.

HORSE-BOOT.

SPECIFICATION forming part of Letters Patent No. 416,579, dated December 3, 1889.

Application filed May 27, 1889. Serial No. 312,336. (No model.)

To all whom it may concern:

Be it known that I, MICHAEL DEBATIN, of the city of St. Louis, in the State of Missouri, have invented a certain new and useful Improvement in a Device to Prevent Interfering in Horses, of which the following is a full, clear, and exact description, reference being had to the accompanying drawing, forming part of this specification.

10. This is a device to prevent horses striking the hoof against the fetlock. It consists of a padded strap surrounding the leg above the fetlock and having a horizontal flexible projection.

15. The drawing is a perspective view of the device, showing it applied to the leg of a horse, the position of the leg being indicated by broken lines.

20. The strap is seen at 1, having a buckle 2, beneath which is a pad 3, which is shown to be made of felt. The strap passes between two pieces of leather 4 and 5, connected by stitching all around the margin, except in the places where the strap 1 passes through. To 25 the inner piece 4 is secured a pad 6, which rests against the inner side of the leg, while the pad 3 rests against the opposite or outer side of the leg. To the outer piece 5 is secured the projection or fender 7, which projects directly inward from the leg. The fender has an outer piece 8, bent in a U 30 form, and whose ends 9 are turned outward and lie flat on the face of the part 5, to which they are firmly attached by rivets 10. Within

the piece 8 is a straight piece 11, serving to 35 stiffen the fender and secured in position by rivets 12, as shown, passing through the fender, or by stitching, or both. The fender has sufficient stiffness to retain its position, except when struck by the foot or leg of the horse, 40 at which time it bends and allows the leg to pass without shock or injury, at once regaining its natural position.

There is nothing to cause any noise or to strike the leg with violence, or to lap around 45 the leg, so that it may be used upon the most timid or fractious horse without causing fear or excitement.

The fender may be formed wholly of rubber, or the part or piece 11 be formed of rubber while the part or piece 8 is of leather. 50

I claim as my invention—

1. The device to prevent interfering in horses, having a strap 1, and a fender consisting of a bent outer piece 8, secured to 55 strap 1, and a stiffening-piece 11 within it, substantially as set forth.

2. The combination of the strap 1, the pieces 4 5, secured together, between which the strap passes, the pads 3 and 6, and the flexible 60 fender projecting horizontally from the padded base of part 5, substantially as and for the purpose set forth.

MICHAEL DEBATIN.
